UNITED STATES PATENT OFFICE.

JOSEPH B. GREEN, OF SEATTLE, WASHINGTON, ASSIGNOR TO MONARCH ENGINEERING COMPANY, OF SEATTLE, WASHINGTON, A CORPORATION.

GOLD-SAVING DEVICE.

1,123,188.

Specification of Letters Patent. Patented Dec. 29, 1914.

Application filed November 22, 1913. Serial No. 802,446.

To all whom it may concern:

Be it known that I, JOSEPH B. GREEN, citizen of the United States, residing at Seattle, in the county of King and State of Washington, have invented a certain new and useful Improvement in Gold-Saving Devices, of which the following is a specification.

My invention relates to improvements in vanning devices that are adapted for separating precious metals from their ores and the object of my improvement is to provide a device of this class that shall be especially adapted for separating fine or float gold from gold bearing sand or gravel. I accomplish this object by devices illustrated in the accompanying drawings in which—

Figure 1 is a view in longitudinal section of a structure embodying my invention; Fig. 2, is a plan view of the same showing certain parts broken away better to illustrate certain other parts; Fig. 3, is a view in cross-section on broken line $a-a$ of Fig. 2; Fig. 4, is a fragmentary view in perspective illustrating a detail of my invention and Fig. 5, is a fragmentary view of a detail of my invention.

Referring to the drawings, throughout which like reference numerals indicate like parts, 6 is a side-shaking vanner frame which is carried on supporting bars 7 that rest on a supporting frame 8, a shaft 9, provided with offset or eccentric portions 10, 11 and 12 and with a belt pulley 13 is suitably journaled on one side of the frame 8 and may be connected with a source of power (not shown) by a belt 14. The eccentric portions 10, 11 and 12 of the shaft 9 are each connected with the bottom side 15 of the vanner frame 6 by connecting links 15, 15 as clearly illustrated in Fig. 3 and are adapted to impart a side-shaking motion to such vanner frame 6.

16 is a distributing box into which ore, as gold bearing sand or gravel may be fed by a conveyer 17. The distributing box 16 is provided with the usual spaced blocks 18 and empties onto a screen 19 which has its lower edge secured to the top edge of a sluice box 20 and which serves to separate the coarse ore from the fine ore, the coarse ore passing over the screen 19 and being deposited in the sluice box 20 and the finer ore passing through the screen 19 and falling on another screen 21 that is placed on

the top of an amalgamated copper plate 22 upon which it moves slowly toward the discharge end of the machine and thence, drops a slight distance and passes between two other amalgamated copper plates 23 and 24, which plates 23 and 24 may also be protected by having rifle bars or screens similar to the screen 21 placed upon their amalgamated surfaces. After passing for a considerable distance between the plates 23 and 24 the finer ore falls into a trap 25 which is filled with a solution of sodium amalgam. The plate 23 extends within the trap 25 and covers the sides and bottom thereof and the plate 24 extends within such trap 25 to within a few inches of the bottom, thus the ore entering the trap 25 from between the plates 23 and 24 must enter near the bottom of such trap 25 and become thoroughly immersed in the sodium amalgam to amalgamate gold platinum and other rare metals that may have escaped the plates 23 and 24.

A plurality of recesses 26, 26, are provided in the bottom of the trap 25 in which the rare metals may settle and a rotary agitator 27 mounted on a shaft 28 that is provided with a belt pulley 29, by means of which it may be driven, is also provided to extend lengthwise within the trap 25 and is adapted to be rotated in the direction indicated by the arrow to cause the pulp to pile up on the lower side of the trap 25 and to pass over the lower edge of such trap. The pulp thence moves toward the discharge end of the machine over a blanket 31 of cocoanut matting, burlap or the like, which is spread upon and covers a copper plate 30 and which has transverse riffles 32, 32 that are secured together by bars 33, 33 placed on its upper surface. A screen 34 is placed on the top of the bars 33, 33 and another blanket 35 of cocoanut matting or burlap is spread upon and covers the screen 34.

For the purpose of preventing the screen 20 from loading or clogging I have provided directly below said screen 20 a plurality of automatic hammers or vibrators 36 that each have one end pivotally mounted on a shaft 37 and are adapted to rest their other ends on a cross bar 38 such vibrators 36 being adapted to be actuated by a shaft 39 which is provided with a plurality of offset portions or crank arms 40, 40 as illustrated in Fig. 5, the outer end of such shaft being pro-

vided with a belt pulley 41 by which it may be rotated. The shaft 39 is so disposed that, when it is rotated the offset portions 40, 40 will engage with the lower sides of the vibrators 36 at points near the pivot shaft 37 thus causing the free ends of the vibrators to move quickly upward to strike against the lower surface of the screen 19 to jar loose any particles of sand, gravel or the like 10 that may tend to lodge in the meshes of said screen.

The sluice box 20 is lined with a blanket 43 of Brussels carpet, burlap, cocoa matting or the like, and is provided with riffles 44 15 which extend crosswise thereof.

When operating my device, power may be applied to the pulley 13 to rotate the shaft 9 thus to impart a transverse shaking motion to the vanner frame 6 and at the same time 20 ore and water may be fed into the distributing box 16 and may pass downwardly onto the screen 19, the coarser ore passing over screen 19 into the sluice box 20 and the finer ore falling through such screen 19 onto the 25 screen 21 and the amalgamated plate 22 where a portion of the gold is retained, the fine ore moving toward the discharge end of the machine and entering between the amalgamated plates 23 and 24 which serve to 30 catch and retain more of the gold, the upper plate 24 catching the flour and float gold and the lower plate 23 catching the heavier particles. The finer ore then passes into the trap 25 where it is thoroughly immersed in 35 a solution of sodium amalgam and is thoroughly agitated by the agitator 27 in order that gold, platinum and other rare metals may be amalgamated and settle into the recesses 26 that are provided in the bottom 40 of the trap 25. The agitator 27 which rotates in the direction indicated by the arrow causes the pulp in the trap to pile up and to pass over the lower edge of the trap 25 and on to the blanket 31 of burlap, cocoanut mat-

ting or the like, which lies on top of the 45 plate 30. The pulp then works over the successive riffles 32, 32 which riffles 32, 32 catch and hold any gold that may settle to the bottom and such pulp is finally discharged from the end of the machine, the blanket 34 on the 50 top of the screen 35 preventing any particles of fine gold from becoming dry and floating away. The coarser ore passes into the sluice box 20 and moves downwardly toward the discharge end of the machine over the 55 blanket 43 and the riffles 44 such riffles 44 and blanket 43 serving to catch any gold that may be carried over with such coarser ore.

Obviously changes in various details embodied in my invention may be made without departing from the spirit thereof or sacrificing any of its advantages.

What I claim is:

1. The combination with a shaking trough, 6 of superposed amalgamated plates therein forming a passage, a trap at the lower end of said plates, the upper of said plates being deflected into said trap and terminating near the bottom thereof, and agitating means 7 in the trap in proximity to the outlet of the passage formed by said plates.

2. The combination with a shaking trough, of a trap located intermediate the length of said trough, a blanket section in the trough immediately beyond said trap, riffles upon said blanket, a screen slightly spaced above the riffles, and a blanket upon said screen, said screen and its blanket being positioned to divide the stream of pulp issuing from said trap.

In witness whereof, I hereunto subscribe my name this fifteenth day of November A. D., 1913.

JOSEPH B. GREEN.
